United States Patent Office

Des. 185,063
Patented May 5, 1959

185,063

CREAMER

Lancaster P. Clark, Jr., Fairfield, Conn., assignor to
Clark Metal Products, Inc., Fairfield, Conn., a corporation of Connecticut

Application December 27, 1957, Serial No. 49,050

Term of patent 7 years

(Cl. D44—21)

Fig. 1 is a front elevational view of a creamer showing my new design;

Fig. 2 is a side elevation;

Fig. 3 is a top plan view;

Fig. 4 is a vertical sectional view, taken along the line 4—4 of Fig. 3;

Fig. 5 is a vertical sectional view, taken along the line 5—5 of Fig. 3.

I claim:

The ornamental design for a creamer, substantially as shown.
